GAME BOARD

Gardner Royce, Coral Gables, Fla., assignor, by decree
of distribution, to Joe B. Royce

Filed Mar. 24, 1958, Ser. No. 50,157

Term of patent 14 years

(Cl. D34—5)

Fig. 1.

Fig. 2.

Figure 1 is a plan view of a game board embodying my new design; and

Figure 2 is a view of the bottom side of the game board shown in Figure 1.

The game board is of conventional thickness.

The drawing is shaded to illustrate contrast of color.

The essential features of the design are shown in full lines.

What I claim is:

The ornamental design for a game board, as shown and described.
